(57) **CLAIM**

The ornamental design for a cartridge for respiratory apparatus, as shown and described.

DESCRIPTION

FIG. 1 is a front elevational view of a cartridge for respiratory apparatus.

FIG. 2 is a rear elevational view of the cartridge for respiratory apparatus shown in FIG. 1.

FIG. 3 is a right side elevational view of the cartridge for respiratory apparatus shown in FIG. 1. The left side elevational view is the mirror image of the right side elevational view.

FIG. 4 is a top plan view of the cartridge for respiratory apparatus shown in FIG. 1.

FIG. 5 is a bottom plan view of the cartridge for respiratory apparatus shown in FIG. 1.

FIG. 6 is a front right perspective view of the cartridge for respiratory apparatus shown in FIG. 1.

FIG. 7 is a bottom, front right perspective view of the cartridge for respiratory apparatus shown in FIG. 1.

FIG. 8 is a rear right perspective view of the cartridge for respiratory apparatus shown in FIG. 1; and,

FIG. 9 is bottom, rear right perspective view of the cartridge for respiratory apparatus shown in FIG. 1.
